ZALMON G. SHOLES, OF WILMINGTON, DELAWARE, ASSIGNOR, BY MESNE ASSIGNMENTS, TO SHOLES STANDARD TYPEWRITER COMPANY, OF WILMINGTON, DELAWARE, A CORPORATION OF DELAWARE.

TYPE-WRITING MACHINE.

1,162,194.

Specification of Letters Patent. Patented Nov. 30, 1915.

Application filed August 4, 1914. Serial No. 854,907.

To all whom it may concern:

Be it known that I, ZALMON G. SHOLES, a citizen of the United States, residing at Wilmington, in the State of Delaware, have invented certain new and useful Improvements in Type-Writing Machines; and I do hereby declare the following to be a full, clear, and exact description of the invention, such as will enable others skilled in the art 10 to which it appertains to make and use the same.

My present invention relates to improvements in typewriting machines, and is intended to provide a simple, effective and 15 durable mechanism which may be used with a very light touch, and in which the parts may be readily assembled or disassembled.

My invention will be more clearly understood by reference to the accompanying 20 drawings, in which similar parts are indicated by similar reference symbols throughout the several views.

Figure 1 is a longitudinal elevation of such parts of a typewriter as will illustrate 25 my invention, the other parts being omitted for the sake of clearness in the drawings; Fig. 2 is a detail showing the type lever and certain other parts disconnected from the machine; Figs. 3 and 4 are, respectively, a plan view and front elevation of a special form of bearing rod adapted to be used in the invention; Fig. 5 is a front view of the segment to which the type levers are attached; Fig. 6 is a perspective view of a portion 35 of the segment shown in Fig. 5; and Fig. 7 is a similar view of a portion of the bearing rod used in said segment.

18 represents one of the key levers having its heel slotted, as at 22, see Fig. 2, with an 40 enlarged recess 21 adapted to engage the rounded portion 10 of the bearing rod, while the slot 22 permits the heel of said lever to be freely slid over the notched portion 11 of said rod. The ends of the rod pass through 45 the end lugs 16 and 17 of the segment 12, and are adjustably connected in place by nuts 32 and 33, engaging the screw threads 15, provided on the ends of the rod as shown in Fig. 5. This key lever 18 has hinged 50 thereto, as at 18', the link 19 which is hinged to the upper end of the upright lever 20; and this lever 20 is journaled at 25 on a

similar bearing rod to that shown in Figs. 3, 4 and 7, and is provided with a pivot bearing 23 adapted to fit the rounded portion 10 55 of the bearing rod, and with a slot 24 adapted to slip over the notched portions of said bearing rod, so that when said bearing rod is moved a slight distance in one direction the upright levers may be all slid into place, 60 and then a slight backward movement of the bearing rod will cause the rounded portion of same to lock all of said levers in their pivot bearings.

The lower end of the upright lever 20 65 is provided with a cam groove 27, into which projects the pin or roller 28 carried by the key lever 29. This key lever 29 is notched, as at 30, to form a pivot bearing engaging the part 30^a, and is held in engagement with 70 said part 30^a by means of the adjustable coil spring 31, which spring also serves to restore the key lever, also the upright lever, and the printing lever to the normal position ready for operation, which is that 75 shown in Figs. 1 and 2.

It will be noted that as the key lever 29 is depressed, the pin 28 will slide down the lower side of the cam groove 27, pressing the heel of the upright lever backward, and 80 swinging the type lever upward and forward with an accelerated motion due to the shape of the cam groove 27. When the key lever 29 is released, the spring 31 will pull the pin 28 upward against the upper face of 85 the cam groove 27 and will restore the type lever 18 to the initial position shown in Fig. 1, which movement of the type lever will also be supplemented by the weight of the 90 free arm of the type lever.

By properly shaping the lower engaging face of the cam groove 27, the desired touch may be secured for the instrument, and the swinging movement of the type lever may be effected with the acceleration desired. 95

By having the bearing rod notched as shown in Figs. 3, 4 and 7, the type levers may be quickly and readily applied to the segment 12, and the upright levers 20 may be readily and quickly applied to their bearings 25. Moreover any defective lever can be removed, when desired, by simply shifting the bearing rod through a sufficient distance to allow the notches 11 to coincide with 100

the slots 22 or 24, as the case may be, when any or all of the levers in the set may be removed if desired.

Having thus described my invention what 5 I claim and desire to secure by Letters Patent of the United States is:—

In a typewriting machine, the combination with a type lever pivoted at its heel to the frame of the machine, and provided with 10 a laterally-projecting lug on its heel, a key lever provided with a pin near its forward end, a spring normally holding said key lever in the raised position, a centrally pivoted upright lever having its heel provided 15 with a cam groove adapted to engage said pin on the key lever, and a link connecting the upper end of said upright lever and said lug on the heel of said type lever, with

means for detachably connecting said type lever and said upright lever, respectively, 20 to their pivots, comprising rounded pivot bearings provided in said levers opening into narrower slots therein, and bearing rods having notched portions adapted to pass freely into said slots, said rods being provided with rounded bearing portions adapted 25 to register with said rounded pivot bearings in said levers, and to lock said levers in place, when said rods are moved longitudinally, substantially as described. 30

In testimony whereof, I have affixed my signature, in presence of two witnesses.

ZALMON G. SHOLES.
